UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

COAL-HANDLING SYSTEM.

1,425,822.

Specification of Letters Patent. Patented Aug. 15, 1922.

Application filed March 26, 1921. Serial No. 455,901.

To all whom it may concern:

Be it known that I, FRANKLIN E. ARNDT, a citizen of the United States, residing at Galion, in the county of Crawford and 5 State of Ohio, have invented certain new and useful Improvements in Coal-Handling Systems, of which the following is a specification.

This invention relates to elevator and 10 handling systems, and particularly to those handling systems which are principally used for handling coal but which may be used for handling other materials wherein the coal or other material is discharged 15 from a car, is then elevated by means of a bucket, and is then carried by the system to a point of discharge.

In certain systems known to me and 20 which are in general use today, the coal is discharged from the car into a bucket which is carried upward to a suitable height, then carried laterally to the point of discharge and then the bucket is opened to discharge the coal or the bucket is lowered 25 toward the coal dump so as not to break the coal, and the bucket opened to discharge the coal. The bucket is then raised again, carried back to the point where it was initially elevated and lowered into position to 30 receive a fresh charge from the car. Such a system as this involves a considerable loss of time, inasmuch as the single bucket is carried through the path above described.

The general object of my invention is 35 to provide a system which will not involve this loss of time and wherein an elevator bucket is used by which the coal or other materials are elevated from the car level to any desired height, and in which a 40 secondary or travelling bucket is used into which the first named bucket discharges, which travelling bucket is then shifted to the point of discharge and discharged while the first named bucket or elevator bucket 45 is returned to its receiving point.

A further object is to provide a construction of this character in which the movement of the two buckets may be controlled by a single operator.

50 Other objects will appear in the course of the following description.

My invention is illustrated in the accompanying drawings, wherein:

55 Figure 1 is a diagrammatic elevation of my elevating and conveying or coal handling system;

Figure 2 is a side elevation of the structure shown in Figure 1;

Figure 3 is an elevation of the bucket and the carrier therefor partly in section;

Figure 4 is an end elevation of the supporting rail and its sheaves;

Figure 5 is a fragmentary end elevation of the lower end of the bucket;

Figure 6 is a side elevation of the outer 65 end of the supporting rail 24 and the sheaves connected therewith;

Figure 7 is a top plan view of the construction shown in Figure 6;

Figure 8 is a front elevation of the cable 70 controlling drums;

Figure 9 is an end elevation of the cable controlling drums;

Referring to these drawings, and particularly to Figures 1 and 2, it will be seen 75 that I have provided that the coal is hoisted and the hoisting bucket discharged to receiving position by means which is described, illustrated and claimed in my Patent #1,318,472, granted on the 14th 80 day of October, 1919. The structure for primarily hoisting the coal comprises a tower, designated 10, which may be of any suitable construction and which is provided with upwardly extending guides 11. The 85 lower ends of these rails or guides extend down into a pit 12, into which discharges a laterally disposed chute 13, the upper open end of this chute being disposed beneath the track supporting the car A. The discharge 90 from this chute is controlled by a movable chute section 14, which in turn is controlled by an operating lever or other suitable means. Coacting with the rails 11 is a bucket 15 which, in its receiving position, is disposed within the pit 12, the chute section 14 when it is lowered discharging into this bucket and when it is raised permitting the bucket to move vertically upward on the rails 11 toward the 100 upper end of the tower 10.

The rails or trackways 11 at their upper ends turn laterally, as at 16, the bucket having wheels adapted to be shifted onto said laterally projecting section to overturn the bucket. The bucket is connected by a cable to a hoisting means. This cable at one end is operatively connected to the bucket and passes over a pair of wheels 17 mounted upon the upper end of the tower 110 and then passes downward to a change direction wheel 18, then diagonally down-

ward to a second change direction wheel 19, and then downward and laterally over a wheel 20 and then directly downward to the primary hoisting drum 21. When this 5 drum is rotated in one direction, the bucket 15 will be raised until it reaches the laterally directed portion 16 of the track. The bucket shifts outward on this track and overturns to discharge its contents. When 10 its contents have been discharged, the bucket is returned to its initial position in the pit 12. The mechanism above described is well known and is that described in my patent before referred to. Hence 15 no detailed description of this hoisting means is believed to be necessary.

The coal which is discharged from the bucket 15 is intended to be discharged into a second bucket or carrier, this being mounted 20 for movement upon a supporting structure into any desired location over a dump. This secondary supporting structure, which extends laterally or in any other desired direction from the tower 10, is designated 25 generally 22 and is made up of angle or channel iron providing a plurality of supporting legs 23, as they may be termed, connected at intervals by transverse and diagonal braces, struts, and tie rods. The details 30 of this structure involve no invention and, therefore, further destruction is not believed to be necessary.

Carried upon the supporting structure at its upper end and extending longitudinally 35 of the supporting structure is an I-beam 24, and also carried on the supporting structure in such position that it will receive the coal discharged from the bucket 15 is a hopper 25 which discharges downwardly and toward 40 the point beneath the I-beam 24. The carrier whereby the secondary bucket is supported to travel upon the I-beam 24 consists essentially of two oppositely disposed webs or plates 26 having four supporting 45 wheels 27 disposed at the upper corners of the plates and running upon the lower flange of the I-beam 24. The plates 26 forming the carrier are rigidly braced from each other in any suitable manner forming 50 no part of this invention but which is illustrated in detail in my application for patent filed of even date herewith.

For the purpose of shifting this carrier longitudinally along the beam 24, I mount 55 at one end of the beam the bracket 28 (Figs. 6 and 7) which carries the horizontally disposed grooved wheel or sheave 29 and also carries the pair of vertically disposed grooved guide wheels 30 which are so related 60 to the wheel 29 as to prevent a cable from running off this wheel 29. At the opposite end of the beam 24 there is supported a yoke 31 (see Fig. 4) which depends below the beam and which carries upon it four 65 grooved wheels or sheaves 32, 33 and 34 and

35. Attached to the carriage 26 is a cable 36 which extends from the carriage over one of the wheels 30, then around the wheel 29 and then longitudinally over the other wheel 30 and passes over the wheel 32 and 70 then downward to one of the hoisting drums, as for instance the hoisting drum 37 (Fig. 8) which is disposed in alignment with the hoisting drum 21 and is disposed at the base of the tower 10 or in any other 75 suitable location.

To the other end of the carriage is connected the cable 38 which extends over the grooved wheel 33 or transmission cable sheave, then extends downward to the drum 80 39 which is disposed immediately adjacent the drum 37 and preferably upon the same shaft. These drums are capable of being independently driven and independently released from the driving means so that when one drum is operated one of the cables, as for instance the cable 36, will be wound up on the drum and the other cable 38 paid out, and when the other drum is operated, the cable 36 will be paid out and the cable 90 38 wound up on the drum. Therefore, the carriage can be by this means shifted longitudinally upon the track formed by the I-beam 24 to any desired position. The carriage is limited in its movement merely by 95 the stop blocks 40 mounted upon the I-beam.

The bucket, which is designated 41, is supported by means of a cable so that the bucket may be raised and lowered. To this 100 end, the carriage 26 is provided with a pair of grooved wheels 42 disposed between the plates forming the carrier 26. The bucket 41 is supported by means of a pair of channel irons 43 disposed above the bucket, to the ends of which channel irons are attached the downwardly extending hangers 44 which are oscillatably engaged with outwardly projecting trunnions 45 on the bucket in any usual or suitable manner. 105 Also attached to these channel irons 43 and extending upward therefrom above the channel irons are supporting brackets 46 which support the pulley 47. The cable 48 is attached at one end to the bracket 28 110 and extends therefrom longitudinally of the beam 24, extends over one of the pulleys 42, then downward and beneath the pulley 47, then up and over the other pulley 42, then laterally and over the sheave 35, this elevator cable then passing downward over the hoisting drum 49 disposed at the base of the tower 10 and in line with the drums 21, 37 and 39. By operating the drum 49, therefore, it will be obvious that the bucket 41 may be raised or lowered, and by operating the drums 37 and 39 it will be obvious that the carriage 26 with the bucket 41 may be shifted longitudinally upon the I-beam 115 24 to any desired position on the structure 120 125 130

22. When the carriage with the bucket has been shifted to the desired position, the bucket is lowered, the bottom of the bucket is caused to open in a manner which will be 5 later stated, and thus the bucket is discharged. The bucket 41 is then raised to its original position once more and the drums 37 and 39 are manipulated so as to cause the carriage to travel back to its original position 10 and the bucket 41 to be so disposed as to receive material from the hopper 25.

While I do not wish to be limited to any particular manner of so constructing the bucket that it will open to discharge its contents when it is lowered and automatically close to receive a new charge when raised, I have illustrated for this purpose the bucket which is fully described and claimed in my pending applications for patent filed of even 15 date herewith, Serial #455,902 and 455,903, but this is purely illustrative and I do not wish to be limited to this particular construction, as other buckets adapted to operate in this manner might be used.

25. The bucket 41 is shown as being provided at its lower end with two doors 50 hingedly mounted at 51 upon the side walls of the bucket and normally disposed in a downwardly convergent relation but capable of 30 swinging into a parallel vertical position. Attached to the ends of these doors and exteriorly of the end walls of the bucket are the irons 52 angularly bent at their upper ends, through which angular bent ends pass 35 rods 53, which in turn extend through coiled compression springs 54 and are provided with nuts or heads at their lower ends bearing against these springs. The upper ends of these rods are engaged with cables 55 40 which pass over the sheaves 56 mounted upon the end walls of the bucket. These cables then extend upward, two cables at each end of the drum, and are engaged with the pairs of winding wheels 57 which are operatively mounted at the ends of and upon the 45 I-beams 43. Each pair of these winding wheels 57 is mounted upon a shaft 58, which shaft carries upon it a pinion 59 engaged by a vertically shiftable rack 60 operating in 50 guides 61. When the doors 50 are opened, that is, when they are in their vertical position, the racks 60 are upwardly projected. Coacting with these racks 60 are vertical stops 64 each formed of a U-shaped strip of 55 metal which at its upper end is riveted or bolted to the side plates of the carrier 26.

It will be obvious now, if the doors be 60 opened and the bucket is moving upward, that when the bucket arrives at a predetermined distance from the carrier 26, the upper ends of the rack bars 60 will strike against the stops 64 and as the bucket moves still further upward, these rack bars will be depressed, thus causing the rotation of the 65 shafts 58, the winding up of the small ca-

bles 55, and the consequent closing of the doors, the spring 54 relieving strain.

For the purpose of holding the doors closed until the buckets have lowered sufficiently so as to approximate the pile of material onto which the bucket is to be discharged, I have illustrated in Fig. 5 the bucket as provided with door locking and tripping mechanism comprising crossed supporting bars 65 which are pivoted to the bucket at 66 and to each other at 67. Each bar extends downward, outward and slightly upward at its outer end, and pivoted to the extremity of each bar are a pair of links 68 which at their upper ends are pivotally connected by means of a transverse pin 69 to a pair of links 70, in turn pivoted at its upper end to the door by means of the angle irons 71 and the transverse pin 72. Disposed below the doors are the horizontally extending 75 angle irons 73, these angle irons at their extremities being pivotally connected by means of a transverse pin 74 to the lower ends of a pair of links 75. These links extend upward 80 on each side of the links 68 and are pivoted to the pin 69 which pivotally connects these links to the link 70. The members 75 extend beyond the pin 69 and are provided at their extremities with a cross pin 76 which is adapted to bear against the link 70. When 85 the links 68 and 70 are in line with each other, the doors 50 are held closed, but when the links 68 and 70 are broken at the joint formed by the pintle 69, the links can fold with relation to each other and then the 90 doors 50 will swing open. The breaking of these links 68 and 70 at the joint is caused by the angle iron 73 striking the ground or the pile of material upon which the material in the bucket is to be dumped. When these 95 bars 73 strike the pile, they will be raised, thus shifting the links 68 and 70 into angular relation and permitting the doors to open. As the doors swing downward, they pull on the cables 55. These cause the rotation of 100 the shafts 58 and the consequent upward movement of the rack bars 60. The bucket is now elevated by the hoisting mechanism and when the bucket reaches a proper distance from the carriage 26, the upper ends 105 of the rack bars strike the stop 64 and as the bucket still further rises these rack bars 60 are forced downward, thus rotating the shafts 58 in a reverse direction and winding up the cables 55 upon the wheels 57 and 110 causing the closing of the doors. Other means might be used for the purpose of closing and opening these doors, as before stated, and I do not wish to be limited to the construction illustrated.

115 For the purpose of operating the drums 37, 39 and 49, I mount all of these drums upon a single longitudinally extending shaft, each of these drums being provided with a gear wheel 78 which is engaged with 120 125

a pinion 79 loosely mounted upon a longitudinally extending power shaft 80 driven by any suitable motor. The pinions for the drums 37 and 39 are provided with facing 5 clutch elements 81 and 82, and mounted upon the shaft 80 for rotation therewith and shiftable into or out of engagement with either one of the clutch elements 81 and 82 is the sliding clutch member 83 controlled by a lever 84. When the lever 10 is shifted in one direction, the clutch element 81 will be engaged with the shaft and the drum 39 will be driven, and when the clutch element 83 is shifted in the opposite direction the drum 37 will be driven. 15 When one drum is driven the other runs idly. These drums 37 and 39, as before stated, are operatively connected to the cable whereby the carriage is shifted along the I-beam 24. The drum 49 is likewise driven by a loose pinion mounted upon the shaft 80, this pinion being operatively engageable with the shaft 80 by means of a clutch 85 of any suitable construction actuated by means of the lever 86. When this 20 lever is shifted in one direction, the hoisting drum 49 is operatively engaged with the shaft 80 to thus cause a positive rotation of the hoisting drum and the elevation of the bucket 41. When the clutch is 25 thrown out, however, the weight of the bucket 41 will cause it to descend. The hoisting drum 21 may be operatively connected to the shaft 80 by means of a clutch 87 operated by the lever 88, or is disconnected therefrom by shifting the lever in the opposite direction and thus the hoisting cable of the primary bucket may be raised or lowered to raise or lower the primary bucket. 30

For the purpose of holding the hoisting drums 21 and 49 so as to support the hoisting buckets in their raised positions or releasing said drums to permit the hoisting buckets to move downward, I have associated with each pinion 79 and mounted upon the same shaft brake drums 89 having brake bands 90. Each of these brake bands is engaged by internally screw-threaded collars 91 mounted upon a reversely screw-threaded shaft 92 upon which the levers 86 and 88 are mounted whereby the oscillation of said levers in one direction or the other will cause the brake bands to bind 45 upon the brake drums or release the brake drums. Thus when the corresponding clutch is thrown out by shifting the lever in one direction for a predetermined distance, the corresponding drum will be left free to 50 rotate, but upon a further movement of the lever in the same direction the corresponding brake band will be contracted upon the drum to brake it, and obviously upon the reverse movement of the lever the brake band will be released, and upon a further

movement in the same direction the clutch will be thrown in. The particular driving and controlling means for the brake drums which is illustrated forms no part of my present invention but is to form the subject matter of a separate application for patent. Hence the details of the drum driving and controlling mechanism are not illustrated.

It will be noted that the bucket 41 as 75 illustrated is twice the capacity of the bucket 15, and thus the bucket 15 may have a capacity of 1,400 pounds of coal, while the bucket 41 may have a capacity of 2,800 pounds of coal, or the bucket 41 may have 80 any other desired capacity or the bucket 41 may have a capacity equal to or more than double that of the bucket 15.

In operation, the coal or other material is discharged from the car A into the bucket 85 15 and the operator then throws in the clutch of drum 21 and the bucket 15 is hoisted and discharges into the hopper 25. At this time, the bucket 41 is in its raised 90 and receiving position, as illustrated in Figure 1, and the hopper discharges its contents into the bucket 41. The operator then, by means of the lever 84, connects the drum 37 to the shaft 80, which causes the cable 38 to draw the carriage 26 along the 95 track rail 24 until the point is reached where the coal is to be dumped. The operator then releases the drum 37 from its engagement with the shaft 80 and holds the drum by means of any suitable brake, such for instance as that commonly found on drums of this character, and then releases a like brake on the hoisting drum 49, permitting the bucket to move downward by its own weight until the cross bar 73 strikes 105 any impediment, whereupon the doors are opened and the material is discharged from the bucket 41.

As soon as this has been done, the operator connects the hoisting drum 49 with the 110 shaft 80 by means of the clutch, and the cable 48 is wound up on the drum until the bucket 41 is hoisted sufficiently to close the doors at the bottom of the bucket. The operator then releases the brakes on the 115 shifting drums 37 and 39 and connects the drum 39 with the shaft 80, causing the carriage to return to its original position with the bucket beneath the hopper 25. Where the bucket 41 is twice the size of the bucket 15, the bucket 15 will have to be elevated twice in order to load the bucket 41 but as soon as the bucket 41 is loaded it can immediately move off to its position of discharge simultaneously with the descent of the bucket 15 into the pit 12, and while the bucket 41 is moving to its discharge position and is being discharged, the bucket 15 is being lowered again, thus saving a considerable amount of time over a system 125 130

wherein the bucket 15 is raised and then moved laterally and then lowered to discharge it, then again raised and brought back to its original position and again lowered. It is obvious, of course, that, as stated, the bucket 41 may have a cubical content three or four times greater than that of the bucket 15. In that case, the bucket 15 would have to be raised three or four times before the bucket 41 would be filled, but the principle of operation remains the same.

While I have illustrated certain details of construction as regards the drums for operating the buckets, as regards the construction of bucket 41, and the means whereby its doors are opened and closed, I do not wish to be limited to these details, as other means might be provided for controlling the movement of the buckets and controlling the opening and closing of the doors of the bucket 41.

I claim:

1. A handling system including in combination a material carrying bucket movable in an approximately horizontal plane toward or from a charge receiving position, manually controlled means for raising or lowering the bucket, means for discharging the contents of the same, a hoisting bucket, and manually controlled means for raising or lowering the hoisting bucket from and to its receiving position and causing it to discharge into the carrying bucket when the latter is in its receiving position.

2. A handling system including an elevated structure, a carrying bucket operatively supported by said structure and movable therealong from or toward a receiving position and movable vertically with relation to the structure, manually controlled power operated means for shifting the bucket from or toward its receiving position, manually controlled power operated means for raising and lowering the carrying bucket, means for discharging the contents of the carrying bucket when it has been lowered to a predetermined position, an elevating bucket adapted to discharge its contents into the carrying bucket when the latter is in its receiving position, and manually controlled means for raising or lowering the elevating bucket from its receiving to its discharge position and vice versa.

3. A handling system including an elevated structure and carrying bucket operatively supported by said structure and movable therealong from or toward a receiving position and movable vertically with relation to the structure, manually controlled, power operated means for shifting the bucket from or toward its receiving position, manually controlled, power operated means for raising or lowering the bucket, means for discharging the contents of the carrying bucket when it has been lowered

to a predetermined position, a tower forming part of the elevator structure and having tracks, an elevating bucket mounted for movement on said tracks and adapted when hoisted to a predetermined point to discharge its contents into the carrying bucket when the latter is in its receiving position, and manually controlled, power operated means for raising or lowering the elevating bucket.

4. In a handling system, an elevated structure, a carrying bucket operatively supported by said structure and movable therealong from or toward a receiving position, manually controlled power operated means for shifting the bucket from or toward its receiving position, manually controlled power operated means for raising or lowering said carrying bucket when the latter is out of its receiving position, means for causing the discharge of the carrying bucket, a hopper mounted upon the elevated structure and adapted to discharge into the carrying bucket when the latter is in its receiving position, a hoisting bucket mounted upon the structure, means for causing the automatic discharge of said hoisting bucket into said hopper when the bucket is hoisted to a predetermined point, and power operated manually controlled means for raising the hoisting bucket from its receiving to its discharge position and returning the bucket to its receiving position.

5. A handling system including an elevated structure, a carrying bucket operatively supported upon said structure and movable therealong from or toward a receiving position, manually controlled power operated means for shifting the bucket toward or from its receiving position, manually controlled power operated means for raising or lowering the carrying bucket when the latter is out of its receiving position, contact operated means for discharging the contents of the carrying bucket when the latter is lowered, a hopper mounted upon the structure and adapted to discharge into the carrying bucket when the latter is in its receiving position, a hoisting bucket movable from a receiving position to a discharging position above the hopper, means for automatically causing the discharge of the hoisting bucket into the hopper when the hoisting bucket is raised to its discharging position, and manually controlled power operated means for raising or lowering the hoisting bucket.

6. A handling system including an elevated structure, a carrying bucket operatively supported by said structure and movable therealong from or toward a receiving position, manually controlled power operated means for shifting the bucket from or toward its receiving position and including cables and a drum for each cable, manually

controlled power operated means for raising or lowering said carrying bucket and including a cable, a winding drum for the cable, a hopper mounted upon the structure and adapted to discharge into the carrying bucket when the latter is in its receiving position, a hoisting bucket adapted to discharge into said hopper, means for automatically causing the discharge of said hoisting bucket into said hopper when the hoisting bucket is raised to a predetermined point, manually controlled power operated means for raising or lowering the hoisting bucket including a cable and a drum, a driving shaft for said drums, and manually operable means for connecting any one of said drums to the driving shaft and disconnecting it therefrom.

7. A handling system comprising an elevated structure having a supporting horizontally disposed rail, a carrier having wheels engaging said rail, a sheave mounted in one end of said rail, vertically disposed sheaves mounted at the other end of said rail, a cable connected to the carrier passing around the first named sheave and over one of the second named sheaves and then extending downward, a cable connected to the carrier and extending over the other one of said second named sheaves and then downward, power operated manually controlled winding drums to which said cables are connected whereby to shift the carrier backwards and forwards along the rail, a bucket supported by the carrier, a supporting cable connected to the bucket, sheaves mounted upon the carrier and the supporting rail over which said last named cable passes, the cable

then extending downward, a power operated manually controlled drum for the last named cable whereby the cable may be wound up or unwound to raise or lower the bucket, means for automatically discharging the contents of the bucket when the bucket is lowered to a predetermined point, a hopper mounted upon said structure adjacent one end of the rail and adapted to discharge into the bucket when the bucket is in its receiving position at this end of the rail, a hoisting bucket mounted upon the structure for movement toward or from a discharging position above said hopper, a cable connected to the hoisting bucket, a sheave mounted upon the structure and over which said cable passes, and a power operated manually controlled winding drum coacting with said cable.

8. A handling system including in combination a material carrying bucket movable toward or from a charge receiving position, a vertically movable hoisting bucket adapted when raised to discharge into the carrying bucket when the latter is in its charge receiving position, manually controlled means for raising or lowering the carrying bucket, manually controlled means for shifting the carrying bucket toward or from its charge receiving position, manually controlled means for raising or lowering the hoisting bucket from and to its receiving position, all of said manually controlled means being located in relatively close proximity to each other, and means for discharging the contents of the carrying bucket.

In testimony whereof I affix my signature.

FRANKLIN E. ARNDT.
